UNITED STATES PATENT OFFICE.

EDWIN F. MOWER, OF BOSTON, MASSACHUSETTS, ASSIGNOR, BY DIRECT AND MESNE ASSIGNMENTS, TO THE UNITED SHOE MACHINERY COMPANY, OF PATERSON, NEW JERSEY.

WORK-GAGE.

SPECIFICATION forming part of Letters Patent No. 656,725, dated August 28, 1900.

Application filed June 15, 1899. Serial No. 720,675. (No model.)

To all whom it may concern:

Be it known that I, EDWIN F. MOWER, a citizen of the United States, residing at Boston, in the county of Suffolk and State of Massachusetts, have invented certain new and useful Improvements in Work-Gages; and I do hereby declare the following to be a full, clear, and exact description of the invention, such as will enable others skilled in the art to 10 which it appertains to make and use the same.

The present invention relates to an improvement in work guiding or gaging devices for shoe machinery, and more particularly to a work guiding or gaging device for machines operating upon the soles of boots and shoes, such as outsole-stitching machines, pegging-machines, and machines of like character.

Shoes are now commonly made with soles 20 the edges of which project varying distances beyond the upper, such as the well-known "Baltimore-edge" shoe, wherein the sole along the outer ball portion extends out a greater distance beyond the upper than it 25 does around the toe and along the inner ball and shank portions. In stitching the soles of such shoes the line of stitches as they appear on the upper surface of the sole must be so positioned with reference to the upper 30 that after the sole has been trimmed to follow the line of the stitches the desired variation in the projection of the edge of the sole beyond the upper will be secured.

The object of the present invention is to 35 provide an auxiliary work-gage for machines of the type mentioned of simple construction and preferably so formed and arranged as to be operated by the feeding of the work as the operation upon the shoe-sole is being per-

40 formed.

To the above end the present invention consists of the devices and combinations of devices which will be hereinafter described and claimed.

45 The present invention is illustrated in the accompanying drawings, wherein the invention is shown as being embodied in a stitch-forming machine—such, for example, as the

machine disclosed in Letters Patent of the United States No. 563,871, dated the 14th 50 day of July, 1896.

Figure 1 shows in side elevation portions of such machine embodying my improved work-gage. Fig. 2 shows a top plan view of the work-support with my improved gage 55 thereon, and Fig. 3 represents a modified form of the invention which will be herein-after referred to.

Similar reference characters will be employed to designate corresponding parts 60 throughout the specification and drawings.

In the drawings, 1 represents a post, which in the machine of the patent hereinbefore referred to is mounted to have vertical reciprocations in a suitable bearing in the base of 65 the machine (not herein shown) and is moved vertically preferably by the spring-actuated mechanism of the patent, whereby the work is clamped between the work-support and the presser-foot 2. Upon the upper end of the 70 post 1 is mounted a bed or table 3, the forward end of which is provided with a work-support 4, having a throat 5, through which the needle or other instrumentality operating on the sole of the boot or shoe is arranged 75 to work. The shoe being operated upon rests upon the work-support 4, as shown in Fig. 1 of the drawings, and it will be clearly understood that the extent of projection of the shoe-sole beyond the throat 5 will determine 80 the location of the path of operation of the tool of the machine relatively to the upper of the shoe or the edge of the sole. In stitching a shoe of the type hereinbefore mentioned, wherein the sole projects varying distances from the upper, it is usual in these 85 machines to guide the shoe by the presser-foot while stitching along the shank portions and along the inner ball portions and around the toe. Said presser-foot, as shown in Fig. 1 90 of the drawings, is usually positioned to engage the crease between the upper and sole and bearing against the upper, and inasmuch as the edge of the sole when the shoe is guided by the presser-foot extends some distance in- 95 ward or to the right, as shown in Fig. 1 of the

drawings, beyond the throat 5 the stitches along those portions of the shoe-sole will be placed relatively close to the upper.

As the stitching progresses from the shank 5 to the toe on the outer side of the shoe-sole it becomes necessary that the shoe be gradually moved outward or toward the left, as the machine is shown in Fig. 1, in order that the edge of the sole will project less and less to 10 the right of the throat 5, thus placing the stitches nearer the edge of the sole and farther from the upper, to secure which result the auxiliary gage, which will be described, has been produced. The auxiliary gage 6 is in 15 the present machine preferably formed of an eccentric disk or wheel mounted on a stud 7, carried by the bed or table 3 and about which the gage is free to turn. The eccentricity of the gage is such that as it is turned 20 in the direction of the arrow shown in Fig. 2, which represents substantially its normal position and the position which it occupies while the work is being guided by the presser-foot 2, its periphery will gradually approach nearer to the throat 5 and will thereafter gradually recede from the throat 5, moving the edge of the shoe-sole gradually outward and permitting it to be moved gradually inward as the stitching proceeds along 25 the outer ball portion. The gage 6 is provided with a milled or roughened edge 8 along a portion of its periphery, whereby the contact of the shoe therewith as the shoe is moved along as the sewing progresses gradually 30 turns the gage 6 about the stud 7, varying the position of the shoe-sole with reference to the throat 5, as hereinbefore explained. Any suitable means may be provided to return the gage 6 to its normal position after it has been 35 actuated, such as the spring 9, one end of which is secured to the stud 7 and the other end to the upper surface of the gage 6 by means of a screw 10, the arrangement being such that as the gage 6 is turned in the direction of the arrow, as shown in Fig. 2, it 40 will gradually wind up the spring 9, and as the shoe is removed from contact with the gage 6 the spring 9 will return the gage to its normal position. The periphery of the gage 45 50 along one portion is preferably made smooth, so that when such portion has been brought opposite the throat 5 by the turning of the gage the gage ceases to turn and there will be no restraint to the free movement of the 55 edge of the shoe-sole past the gage.

In order to maintain the gage in its normal position during the sewing of the sole along the shank and around the toe and inner ball portions, I have provided a suitable locking 60 device, which in the illustrated embodiment of the present invention consists of a lever 11, fulcrumed at 12 to the under surface of the bed or table 3 and carrying at its forward end a locking-bolt 13, which passes up through 65 an aperture 14 in the bed or table 3 and engages an aperture 15, formed in the under

surface of the gage 6, the lever 11 being held in its locking position by means of a spring 16, secured to the under surface of the bed or table 3 and projected beneath the forward 70 end of the lever 11. The lever 11 is provided with a projected thumb-piece 17, arranged to be engaged by the operator as desired to remove the locking-bolt to permit the gage 6 to be moved, as hereinbefore described. 75

If desired, the normal position of the gage 6 with reference to the throat 5 may be rendered adjustable by forming the bed-plate 3 as shown in Fig. 3 of the drawings, wherein the bed-plate is cut out, forming a suitable 80 guideway 18, in which is arranged to slide a plate 19, which at its forward end supports the stud 7 and the gage and also the locking-lever, all as clearly shown in dotted lines, Fig. 3. By sliding the plate 19 along the 85 guideway 18 the gage 6 may be adjustably positioned with reference to the throat 5. Any suitable means may be provided for securing the plate 19 in its adjusted position—such as the set-screw 20, tapped into a threaded bearing 21 of the bed or table and arranged to engage with the edge of the plate 19. 90

In the operation of the present invention while the sewing progresses along the shank, the inner ball portions, and around the top of 95 the shoe the shoe will be guided by the presser-foot 2, and as the sole is sewed along the outer ball portions the operator by lifting the lever 11 and removing the locking-bolt 13 permits the gage 6 to be turned by contact of the shoe with the milled surface as the shoe is fed along, and this turning of the gage 6 gradually moves the edge of the shoe-sole outward and inward with reference to the throat 5, whereby the stitches will be 105 properly positioned relatively to the desired variation in the projection of the shoe-sole. 100

I desire to state in this connection that in so far as I am advised of the state of the art it has never been proposed to produce a variable work-gage actuated by contact therewith of the moving work and that therefore I do not consider the present invention as limited to the details of mechanism which have been illustrated and described. 110 115

Having thus described the construction and mode of operation of the illustrated embodiment of the present invention, I claim as new and desire to secure by Letters Patent of the United States— 120

1. The combination with a tool or tools for operating upon a shoe-sole, of a gage actuated by contact of the moving shoe therewith to vary the path of operation of said tool on the sole, substantially as described. 125

2. The combination with a work bed or table provided with a throat through which a tool or tools operate, of a gage actuated by contact of the moving shoe therewith to vary the position of the work relatively to the 130 throat of the work-plate, substantially as described.

3. The combination with a tool or tools operating upon a shoe-sole, of a gage comprising an eccentric disk actuated by contact of the moving shoe therewith to vary the path of operation of said tool on the sole, substantially as described.

4. The combination with a tool or tools operating upon a shoe-sole, of a gage comprising an eccentric disk having a milled or roughened periphery whereby the contact of the moving shoe therewith serves to turn said gage, substantially as described.

5. The combination with a tool or tools for operating upon a shoe-sole, of a gage comprising an eccentric disk, actuated by contact of the moving shoe therewith, a spring to return said disk to its normal position when released by the shoe and a suitable locking device to maintain said disk in its normal position, substantially as described.

6. A gage for shoe-machines, comprising an eccentrically-pivoted disk having a portion of

its periphery milled or roughened to afford a frictional engagement therewith of the shoe-sole, whereby said disk will be turned as the sole is moved along in contact therewith, and having a portion of its periphery smooth, whereby the turning of the gage will cease when the smooth portion thereof is brought in position to engage the sole, substantially as described.

7. The combination with a work bed or plate having a throat or passage, of a gage comprising an eccentric disk, a slide carrying the gage and being adjustable toward and from the throat or passage and means to maintain the slide in its adjusted position, substantially as described.

In testimony whereof I affix my signature in presence of two witnesses.

EDWIN F. MOWER.
